(57) CLAIM

I claim the ornamental design for a disposable pressed garment folding box, as shown.

DESCRIPTION

FIG. 1 is a front/top/left-side perspective view of a disposable pressed garment folding box in the folded position according to my new design; a folded garment and hanger therein being shown in broken lines and therefore disclaimed;

FIG. 2 is a front elevational view thereof;

FIG. 3 is a rear elevational view of the disposable pressed garment folding box of FIG. 1;

FIG. 4 is a top plan view of the disposable pressed garment folding box of FIG. 1;

FIG. 5 is a bottom plan view of the disposable pressed garment folding box of FIG. 1; and,

FIG. 6 is a side elevational view of the disposable pressed garment folding box of FIG. 1; the other side being a mirror image thereof and therefore not shown.
